UNITED STATES PATENT OFFICE.

JAMES F. LOCKWOOD, OF PHILADELPHIA, PENNSYLVANIA, ASSIGNOR TO
ZACHARY T. HALL, OF SAME PLACE.

DESIGN FOR A STOVE-MAT.

SPECIFICATION forming part of Design No. 22,123, dated January 10, 1893.

Application filed November 19, 1892. Serial No. 452,584. Term of patent 14 years.

To all whom it may concern:

Be it known that I, JAMES F. LOCKWOOD, a citizen of the United States, residing in the city and county of Philadelphia, State of Pennsylvania, have invented and produced a new and original Design for a Stove-Mat, of which the following is a specification, reference being had to the accompanying drawing, showing a part thereof.

The leading feature of my design for a stove mat is the border of the same having its inner periphery of the form of inwardly projecting teeth whose ends or points are truncated, and its outer periphery an unbroken circle.

In the drawing:—A designates a stove mat having a border B. On the inner periphery of said border is a row of V-shaped recesses C, producing teeth whose ends are truncated as at D, forming a broken zig-zag line around said periphery. The outer periphery of the border is an unbroken circle.

What I claim is—

The design for a stove mat as shown and described.

JAMES F. LOCKWOOD.
